ATTYS.

UNITED STATES PATENT OFFICE.

EDMUND F. MOULD, OF CLEVELAND, OHIO, ASSIGNOR TO THE ADAMS-BAGNALL ELECTRIC COMPANY, A CORPORATION OF OHIO.

HOLDER FOR GLOBES OR REFLECTORS.

1,045,588.

Specification of Letters Patent. Patented Nov. 26, 1912.

Application filed September 30, 1911. Serial No. 652,125.

To all whom it may concern:

Be it known that I, EDMUND F. MOULD, a citizen of the United States, residing at Cleveland, in the county of Cuyahoga and State of Ohio, have invented a certain new and useful Improvement in Holders for Globes or Reflectors, of which the following is a full, clear, and exact description, reference being had to the accompanying drawings.

This invention relates to supports or holders for globes or reflectors and more especially to supports or holders of the type that are formed or associated with electric lamp fixtures.

It is the general purpose of the invention to provide a fixture of this type and a globe or reflector with a supporting device which is extremely efficient in operation, convenient and easy of application, and which will firmly and securely support the globe or reflector through and in conjunction with the co-operating features of construction of the fixture, the globe or reflector, and the interposed supporting device, the said device being arranged to engage the opposed portions of the fixture and opposed portions of the globe or reflector.

Generally speaking, the invention may be defined further as consisting of the combinations of elements and parts illustrated in the drawings forming a part hereof and embodied in the claims attached hereto.

In the drawings Figure 1 represents a vertical sectional view taken through a globe or reflector and fixture showing the interposed and co-operating supporting device in position. Fig. 2 represents a sectional view corresponding to line 2—2 in Fig. 1. Fig. 3 represents a sectional detail of a modified form of supporting device, showing its application to a slightly modified construction of holder and globe or reflector.

Describing by reference characters the various parts illustrated herein, 1 denotes an electric lamp fixture adapted to receive and support the socket or receptacle of an incandescent lamp. This fixture is provided, near and a short distance above the bottom thereof, with an outwardly projecting bead 2, providing an inwardly opening annular seat. The lower end of the receptacle is preferably cylindrical, as shown at 3.

4 denotes a globe or reflector, which may

be of sheet metal. This globe or reflector is of ordinary shape, so far as its reflecting portion is concerned. At its upper end it is provided with a neck 5, which is preferably cylindrical in shape and of sufficiently smaller diameter than the lower end of the fixture 1 to fit easily therewithin. Between the top and the bottom of this neck, there is located an inwardly projecting bead 6, said bead forming an outwardly opening groove or seat complementary to the seat 2 and the body of the bead being cut away to provide diametrically opposed slots 7 and 8, for a purpose to be explained hereinafter. The upper end of the shade or reflector is shown as bent inwardly, providing a substantially horizontal flange 9 having a central opening for the lamp (not shown).

The locking device referred to hereinbefore comprises a spring wire which is carried by the globe or reflector and which is adapted to be compressed into the groove or seat provided within the inwardly projecting bead 6 to permit the globe or reflector and the fixture to be brought into operative relation and which, when released, expands into the seat formed within the bead 2. In the drawings, the spring wire of which the locking device is composed is formed as a loop having down-turned fingers 10 projecting inwardly through the slot 7. The upper end of each finger merges with a substantially horizontal shoulder 11, projecting abruptly from the adjacent body portion of the spring wire, which body is formed as a ring comprising two diametrically opposed portions 12, adapted normally to rest within the seat 2, the portions 12 being connected by an inwardly projecting portion 13, which is adapted to extend into the slot 8.

With the parts constructed as described, the operation will be as follows: The locking device is so constructed that it tends to expand and bring the shoulders 11 into engagement with the adjacent edges of the slot 7. When so expanded, the opposed portions 12 rest within the seat 2. The shoulders 11 and the portion 13 opposite thereto project into the diametrically opposed slots 7 and 8. When it is desired to apply a globe or reflector to the fixture, it is necessary only to grasp the fingers 10, thereby compressing the wire loop into the inwardly projecting groove or seat carried by the neck 11.

of the globe or reflector. In this position, the globe or reflector neck may be inserted into place within the lower end of the fixture 1. On releasing the fingers 10, the ring 5 expands and locks the globe or reflector and the fixture together. When so locked, the globe is supported at two diametrically opposed portions, namely at the slots 7 and 8, by the shoulders 11 which extend through 10 the slots 7 and by the portion 13 of the loop which projects into the slot 8. By the construction disclosed herein, the globe or reflector is firmly supported from the holder by the engagement of the outwardly projecting portions 12 of the locking device with the annular seat formed within the bead 2 and the simultaneous engagement of the shoulders 11 and the intermediate portion 13 of said device with the slots 7 and 8 20 respectively.

In Fig. 3. there is illustrated a modification of the invention shown in the preceding figures, such modification consisting in forming the locking device from an angular 25 spring wire, preferably square or rectangular in section, with a correspondingly shaped seat in the fixture and in the groove or recess in the neck of the reflector. In this view, 14 denotes the body of the spring wire, 30 15 the angular annular seat formed in the fixture and 16 the complementary seat or recess formed in the neck of the reflector.

Having described my invention, what I claim is:

35 1. In a device of the character described, the combination of a shade holder having an inwardly opening seat, a globe or reflector having a portion adapted to be fitted within said holder and having an outwardly 40 opening groove arranged complementarily to said seat and provided with substantially diametrically opposed slots, and a locking device consisting of a spring wire interposed between the globe or reflector and the holder 45 and having inwardly projecting end portions adapted to extend through one of said slots and into the interior of the globe or reflector and a portion adapted to extend into the other slot, said device being also 50 provided with portions adapted, by the expansion of said wire, to project into the seat formed in the holder, substantially as set forth.

2. In a device of the character described, 55 the combination of a shade holder having a seat, a globe or reflector having a portion adapted to be fitted to said holder and having a seat arranged complementarily to the former seat, the inner of said seats being 60 provided with substantially diametrically opposed slots, and a locking device consisting of a spring interposed between the globe or reflector and the holder and having inwardly turned end portions adapted to extend through one of said slots and an in-

wardly offset portion adapted to extend into the other slot.

3. In a device of the character described, the combination of a holder having, near the lower end thereof, an annular inwardly 70 opening seat, a globe or reflector having a neck adapted to be fitted within the lower end of the holder and having an annular outwardly opening groove opposed and complementary to said seat, said groove being 75 provided with a plurality of slots, and a locking device comprising a spring loop interposed between the neck of the globe and the holder and having a plurality of portions thereof adapted, by the expansion of 80 the spring, to enter said seat and also having inwardly turned ends projecting through one of said slots into the interior of the globe or reflector, said device also having an inwardly projecting portion bent from said 85 wire and adapted to project into the other slot.

4. In a device of the character described, the combination of a hollow holder having, near the lower end thereof, an inwardly facing 90 seat, a globe or reflector having a neck adapted to be fitted into the lower end of the holder and having an outwardly facing seat said neck being provided with a plurality of slots intersecting said outwardly 95 facing seats, and a locking device comprising a spring loop interposed between the neck of the globe and the holder and having a plurality of portions thereof adapted, by the expansion of the spring, to enter said inwardly facing seats and also having in-turned ends projecting through one of said 100 slots whereby said loop may be constricted into said outwardly facing seat, said device also having an inwardly projecting portion 105 projecting into the other slot.

5. In a device of the character specified, the combination of a holder having an annular inwardly opening seat, a globe or reflector having a neck adapted to be fitted within the lower end of the holder and having an annular outwardly opening seat provided with a plurality of slots, and a locking device interposed between said neck and holder and having a plurality of portions 110 bent outwardly therefrom and adapted to enter said seat by the expansion of said spring and also having a plurality of portions bent inwardly therefrom and adapted to enter said slots, and means whereby said 115 spring may be compressed.

6. In a device of the character specified, the combination of a holder having near one end thereof an annular inwardly opening seat, a globe or reflector having a neck 125 adapted to enter said holder and provided with an annular outwardly opening seat arranged complementarily to the former seat and provided with a pair of diametrically opposed slots, an expansible locking device 130

interposed between the holder and neck, in the complementarily arranged seats and having portions adapted, by the expansion of said devices, to occupy the outer seat, said 5 locking device having end portions projecting through one of said slots and a portion projecting into another slot.

In testimony whereof, I hereunto affix my signature in the presence of two witnesses.

EDMUND F. MOULD.
